UNITED STATES PATENT OFFICE.

JOHN HARRIS, OF CLEVELAND, OHIO.

SAFETY APPLIANCE FOR ACETYLENE-GENERATORS.

1,255,308.

Specification of Letters Patent. Patented Feb. 5, 1918.

Original application filed October 12, 1914, Serial No. 866,194. Divided and this application filed March 22, 1915. Serial No. 16,151.

To all whom it may concern:

Be it known that I, JOHN HARRIS, a citizen of the United States, residing at Cleveland, in the county of Cuyahoga and State of Ohio, have invented a certain new and useful Improvement in Safety Appliances for Acetylene-Generators, of which the following is a full, clear, and exact description, reference being had to the accompanying drawings.

This invention relates to apparatus for generating acetylene-gas of high pressure, such as is used with blow pipes for so called "autogenous welding", the apparatus shown and described herein being of the type disclosed in my co-pending application, Serial No. 866,194, filed October, 12th, 1914, of which this application is a division.

My present invention relates more particularly to safety appliances for use with gas generators, and it has for its object to provide means whereby apparatus of the aforesaid character are rendered absolutely safe and reliable, the means comprising certain safe guards which compel the operator to vent the generator when it is opened for the purposes of draining it, or of supplying it with water or carbid.

A further object of the invention is the provision of safety appliances for attaining this end, that are comparatively simple of construction, easy of operation, and positive of action.

In general terms it may be stated that the invention consists of mechanism for carrying out the above objects, embodying the features of construction, combinations of elements, and arrangement of parts having the general mode of operation substantially as hereinafter fully described and claimed in this specification, and shown in the accompanying drawing, in which Figure 1 is a front elevation of a gas generator equipped with the safety appliances of my invention. Figs. 2 and 3 are fragmentary side elevation of the generator shown in Fig. 1, the first of the figures showing the parts in the positions they occupied when the generator is closed and the second, showing the appliances in ineffective position, so that the filling valve, the sludge valve, and carbid-hopper cover may be opened; Fig. 4 is a perspective view of the top of the generator, with the parts in the position shown in Fig. 3; Fig. 5 is a plan of the

carbid hopper, and the parts connected thereto; Figs. 6 and 7 are central vertical sections of the vent valve, the planes of the respective sections being substantially at right angles to each other; and Fig. 8 is a perspective view of certain parts of the weight motor whereby the carbid feeding mechanism is operated.

Taking up a detailed description of the invention by the use of reference characters, 1 represents the generating chamber of the apparatus above which is supported, upon a neck 2, a carbid hopper 3. The filling opening of the hopper 3 is adapted to be closed by a cover 4 that is clamped to the opening by means of a screw 5 which is threaded through a yoke 6, the ends whereof are pivoted to the hopper on opposite sides of the filling opening. This is in accordance with the usual method of closing receptacles of this kind, and as a safeguard against the same being opened except when the apparatus is in proper condition to permit of such an act, a shield 7 is provided to protect these parts, the same being supported by a suitable number of links 8, 8^a, which are arranged to be swung, by the movement of a plate 9, from the position shown in Fig. 2, to that illustrated in Figs. 3 and 4, and vice versa. The shield 7 comprises a cylindrical wall and a circular end that closes the top of the shield, and opposed links 8 have their upper ends pivoted to diametrically opposite portions of the cylindrical wall of the shield, which in the lower ends of said links are, pivoted directly to the ends of ears 10 and 11 which extend from the hopper 3. The link 8^a has its lower end connected to the ear 10, through a shorter link 12, and the pivotal connection between the links 8 and 12 being in turn connected to the end of the plate 9 by means of a link 13. Because of this construction, when the pivotal point of the links 12 and 8 is swung backward, said links are thrown downward to substantially the plane of the upper ends of the ears 10 and 11, and the shield 7 is tilted on edge, as shown in Figs. 3 and 4.

A rod 14 extends from one to the other of the links 8, and is located so as to engage the edges of the open side of the shield and limit the swing movement of the shield with respect to the links.

The lower end of the plate 9 is pivoted

to the end of an arm 15 that is journaled between the ears 16, which project from the side of the hopper 3. The arm 15 has also pivoted to it a rod 17 which extends down 5 in front of the apparatus and has its lower end attached to the operating handle 18, of a filling valve 19. It will be noted that the upper end of the handle 18 is of segmental formation, the arc of the segmental 10 portion 20 being concentric with the stem 21 of the valve, whereon the arm is fastened. It will be stated that when the handle 18 is in the position shown in Fig. 2, the valve 19 is closed; but when the handle is swung 15 upward through substantially 45° , as in Fig. 3, the valve is open.

The valve 19 has connection with the generating chamber of the apparatus, through the nipple 22 and elbow 23; and at its upper 20 end the valve has connection, through the nipple 24, with a water filling receptacle and water level indicator 25. An overflow pipe 26 is connected to the side of the filling receptacle at an elevation corresponding to the 25 high water level of the generator, indicated by the lines α . Therefore, when the valve 19 is open, the generating chamber may be filled by introducing water into the receptacle 25, by the use of a hose or other suitable 30 means, until the water within the receptacle 25 attains the elevation of its overflow, when it will be known that the level within the generator has reached its maximum height.

35 A sludge valve 28 is applied to the generating chamber 1, near its bottom, below the operating handle 18; and the gate 29 of the sludge valve has connection with said handle, by means of the yoke 30 and the rod 31, 40 which telescopes within a tube 32 that is pivoted to the operating handle. The length of the rod 31 is such as will cause its upper end to abut the upper end of the tube 32, when the gate 29 of the sludge valve is closed 45 and the operating handle 18 is down; and the length of the tube 32 is such as will prevent its withdrawal from the rod 31 when the operating handle 18 is elevated.

From the description thus far it will be 50 seen that neither the cover of the carbide hopper can be removed, nor the sludge valve opened, until the operating lever 18 of the filling valve 19 has been elevated and the valve opened. However, it is essential that 55 the apparatus be exhausted, prior to the opening of the valve 19, and mechanism for preventing the operation of this valve until the apparatus has been exhausted, will be described presently.

60 I will next describe the valve that is illustrated in Figs. 6 and 7, whereby the apparatus is vented in case the pressure therein exceeds a predetermined point, and through 65 which the apparatus is exhausted prior to each operation of the filling valve 19. It

will be observed from the aforesaid Figs. 6 and 7, that the vent valve comprises upper and lower casing members 35 and 36, the adjacent edges of which are each provided with a horizontal flange 37 and 38, respectively. Between these flanges is securely clamped the periphery of a flexible diaphragm 39. The casing member 35 converges toward its upper end and terminates in a cylindrical neck 40 which has applied 75 to it a cap 41, and threaded within the neck, and adapted to be covered by the cap 41, is a spring casing 42, against the top wall of which bears the upper end of a coil spring 43. The lower end of this spring surrounds 80 a shank 44 of a yoke 45 that is formed integral with a disk 46, from the underneath side of which depends a central stud 47. By means of the stud 47, and the nut 48 applied thereto, there is clamped to the disk 46, 85 plate 49, diaphragm 39; and a valve member 50, having an annular pliable contact portion 51, preferably of rubber. The contact portion of the valve member is arranged to engage a seat 52 of corresponding shape, 90 which is located centrally within the lower casing member 36, and is preferably formed by the upper end of an internal tubular extension which projects from one side of the casing, and with which extension is connected 95 the vent pipe 53.

The valve member 50 may be caused to bear upon its seat 52, at any desired pressure, such pressure being obtained by varying the tension of the spring 43 which is accomplished through the adjustment of the casing 100 42, that is threaded into the upper end of the neck 40, said casing 42 being provided with a portion 55 for the application of a wrench or other tool. The lower end of the casing 105 member 36 terminates in an internally threaded boss 56 that has connection, through the pipe 57, with the generating chamber 1. Now, therefore, when the pressure within the generating chamber exceeds that of the 110 tension of the spring 43 the diaphragm 39 will be elevated to remove the valve member 50 from its seat and allow a quantity of gas to escape through the vent pipe 53.

Extending through the yoke 45 is an eccentric 60 upon the shaft 61, journaled in the opposed walls of the upper casing member 35, the same being provided with a suitable packing gland 62 where it passes through the wall of said casing member. 115 Applied to the end of the shaft 61, beyond the packing gland 62, is an arm 63 which has its free end connected, by the link 64, to a lever 65 that is journaled at 66 to a lug 67 projecting from the front of the generating chamber 1. This lever carries a segment 68, the curved face of which is concentric with the pivot 66, and which has a radius equal to the distance between said pivot and the forward end of the handle 18 120 125 130

when the latter is in its lower position; the lug 67 being so located with respect to said handle as to cause the segment of the lever 65, and the segmental portion of the said handle to be in substantially the same plane. It may be stated, also, that the length of the arc of the segmental portion of the valve handle is such as will cause its periphery to just escape one end of the segment 68 when the lever 65 is vertical. Therefore, the handle 18 can be operated only when the lever 65 is in its extreme upper position, and the lever 65 can be operated only when the handle 18 is in its extreme lower position. It is obvious from this that the valve 19 cannot be opened for the purpose of supplying water to the generating chamber, nor can the sludge valve be opened, nor the cover of the carbid hopper removed, until the lever 65 has been elevated to operate the valve 50 and vent the apparatus.

If, through any cause, the pressure within the apparatus becomes excessive and produces a condition which may be considered dangerous, the diaphragm 39 will be elevated to remove the valve 50 from its seat 52 and allow the excess gas to escape through the vent pipe 53, which leads to the exterior of the building. As previously pointed out, the vent valve may be regulated to resist varying degrees of pressure through the adjustment of the spring 43, in actual practice, the spring being adjusted to fifteen pounds pressure, as required by insurance companies.

In case the diaphragm 39 becomes fractured, the gas which would thus escape into the upper portions of the casing would be led off through a branch pipe, which joins the main vent pipe 53.

Having thus described my invention, what I claim is:—

1. The combination with apparatus comprising a generating chamber having a filling valve, the filling valve having an operating handle that is provided with an abutment, of a member movable into and out of the path of said abutment, a vent valve for the apparatus, that is subjected to and adapted to be opened normally by gas pressure within the generating chamber, and connections between the aforesaid movable member and said vent valve whereby the movement of the member out of the path of the aforesaid abutment will open said vent valve.

2. The combination with apparatus comprising a generating chamber and a carbid hopper, and having a filling valve for the former and a cover for the latter, and a shield for the cover of the carbid hopper, the handle of the filling valve having an abutment, of a member movable into and out of the path of said abutment, said member, when in the path of the abutment, prevent-

ing the opening of the filling valve, a vent valve for the apparatus, that is subjected to and adapted to be opened normally by gas pressure within the generating chamber, connections between the operating handle of the filling valve and the aforesaid shield whereby said shield cannot be moved from effective position when said valve is closed, and further connections between the aforesaid movable member and the vent valve whereby the movement of the former out of the path of the aforesaid abutment will open said vent valve.

3. The combination with apparatus comprising a generating chamber having a filling valve, said filling valve having a handle that is provided with an abutment, of a member movable into and out of the path of said abutment, said member when in the path of the abutment preventing the opening of the filling valve, a vent valve for the apparatus that is adapted to be operated normally by the pressure within said apparatus, means tending to seat said valve, connections between the aforesaid movable member and said vent valve whereby the movement of the former out of the path of the aforesaid abutment will open said vent valve, carbid feeding mechanism, a motor for operating said mechanism, a lock for said motor, means tending to hold the lock in effective position, and connections between said lock and the aforesaid movable member whereby the movement of said member into the path of the aforesaid abutment will unlock the motor.

4. In apparatus of the character set forth, the combination with the cover of the carbid hopper and the securing means therefor, of a shield which covers said securing means and extends downward entirely therearound, a pair of links having their upper ends pivoted to the shield at diametrically opposite points and their lower ends pivotally connected to the hopper alongside the cover, the respective upper and lower pivotal points of the links being in axial alinement, a link of substantially the same length as the aforesaid links which has its upper end pivoted to the shield adjacent one of the former links, a shorter link connecting the lower pivotal point of said former link to the corresponding end of the last mentioned link, and means for swinging the shorter link.

5. In apparatus of the character set forth, the combination with the cover of the carbid hopper and the securing means therefor, of a shield which covers said securing means and extends downward entirely therearound, a pair of links having their upper ends pivoted to the shield at diametrically opposite points and their lower ends pivotally connected to the hopper alongside the cover, the respective upper and lower pivotal

points of the links being in axial alinement, a link of substantially the same length as the aforesaid links which has its upper end pivoted to the shield adjacent one of the 5 former links, a shorter link connecting the lower pivotal point of said former link to the corresponding end of the last mentioned link, an abutment carried by and between the first mentioned pair of links and arranged 10 to engage the edge of the shield when the same is moved to ineffective position, and means for swinging the shorter link.

6. In apparatus of the character set forth, the combination of a generating chamber 15 having a filling valve, the filling valve having a rotatable operating handle, a segmental member rigid with said handle and having a peripheral portion concentric with the axis of rotation of said handle, a second 20 segmental member rotatable in the plane of the first segmental member and having a peripheral portion concentric with its axis of rotation, the combined radii of the segmental members being greater than the distance 25 between their axes of rotation, said members being so arranged that one may swing past the end of the other only when

the other is in normal position, a vent valve for the apparatus that is subjected to and adapted to be opened normally by gas pressure within the generating chamber, and connections between the second mentioned segmental member and said vent valve whereby the movement of said segmental member out of the path of the first mentioned segmental member will open said vent valve. 30 35

7. The combination with a gas generating system, of means whereby the system may be opened, a device normally blocking the 40 operation of said means and movable from blocking position, a vent valve constantly subjected to the pressure within a system and capable of being actuated by excessive pressure therein, and connections between 45 said device and valve whereby the movement of said device from blocking position will effect an actuation of the valve.

In testimony whereof, I hereunto affix my signature in the presence of two witnesses. 50
JOHN HARRIS.
